UNITED STATES PATENT OFFICE.

HENRY W. CALDWELL, OF PULASKI, NEW YORK.

DESIGN FOR A BUGGY-TOP SUPPORT.

SPECIFICATION forming part of Design No. 29,156, dated August 2, 1898.

Application filed June 10, 1898. Serial No. 683,135. Term of patent 14 years.

To all whom it may concern:

Be it known that I, HENRY W. CALDWELL, of Pulaski, in the county of Oswego, in the State of New York, have invented and produced a new and original Design for Buggy-
Top Supports, of which the following is a specification, reference being had to the accompanying drawings, forming part thereof.

Figure 1 is a plan view of my buggy-top support. Fig. 2 is a cross-section on line xx , Fig. 1. Fig. 3 is a cross-section on line yy , Fig. 1.

As shown in the accompanying drawings, the leading or material feature of my design consists of a support for the bows of a buggy-top, in the shape of a long trough, cup-shaped

in cross-section, gradually contracting in size from the rear end forward, so as to hold a gradually-tapering top bow of a carriage.

a is the support, gradually expanding from 20 the front end b to the rear end c , as shown.

Having described my invention, what I claim is—

The design for a buggy-top support, as herein described and shown. 25

In witnesss whereof I have hereunto set my hand this 23d day of May, 1898.

HENRY W. CALDWELL.

In presence of—

HOWARD P. DENISON,
MARY A. FRANKLIN.
